ANDREW M. COYLE, OF NEW YORK, N. Y., ASSIGNOR TO OTIS ELEVATOR COMPANY, OF JERSEY CITY, NEW JERSEY, A CORPORATION OF NEW JERSEY.

PLUNGER-EQUALIZER.

955,852.

Specification of Letters Patent. Patented Apr. 26, 1910.

Application filed July 14, 1905. Serial No. 269,586.

To all whom it may concern:

Be it known that I, ANDREW M. COYLE, a citizen of the United States, residing at New York city, in the county of New York and 5 State of New York, have invented a new and useful Improvement in Plunger-Equalizers, of which the following is a specification.

My invention relates to plunger equalizing mechanism and has for its object the provision of simplified and efficient means for equalizing the motion of a plurality of plungers to effect a uniform lifting of a load by the plungers irrespective of the uneven distribution of said load.

More particularly it is the object of my invention to provide improved valves and gearing and means for automatically operating the same to regulate the flow of fluid under pressure to a plurality of plungers and effect 15 the lifting of said plungers at substantially equal velocities irrespective of the load carried by the various plungers.

To these and other-ends appearing hereinafter, my invention consists of the combination, location, construction, and arrangement 25 of the various parts all as more fully explained in the following description and specifically pointed out in the claims.

In the accompanying drawings, Figure 1 30 is a plan view and Fig. 2 an elevation of a platform and hydraulic mechanism for operating the same; Fig. 3 is a sectional view of the preferred form of equalizing valve and also shows the arrangement of differential gears by which said valve is operated; Fig. 3^a is a view of the differential gears taken on the line *a--a* of Fig. 3; Fig. 4 is 35 an elevation of Fig. 3 with a portion broken away to show certain details; Figs. 5 and 6 show respectively a plan and an elevation of 40 a modified form of my invention; Fig. 7 shows a detail of the same; and Figs. 8, 9 and 10 are, respectively, a plan, an elevation and a detail view of my invention applied 45 to valves of ordinary construction.

1 designates a platform to which are secured the plungers 2, 2', 3, 3' near the four corners of the same. These plungers are adapted to move in the hydraulic cylinders 50 10, 11, 12, 13 in a well known manner. These cylinders are fed respectively by the branch pipes 14, 15, 17 and 16. Between the pipes 14 and 15 is connected an equalizing valve mechanism 18 and between the pipes 55 16 and 17 is placed a similar equalizing valve

mechanism 19. The valves 18 and 19 are connected by the pipes 22 and 23 with the main equalizing valve mechanism 20 which is connected to the main supply pipe 21. I associate certain differential gearing with 60 these valves and provide automatic means for operating the same so that the supply of fluid to the plunger cylinders shall be so varied when any one of the plungers tends to assume a position different from that required by the conditions of the apparatus, that the platform will always remain substantially level. For instance if one end of the platform be heavily loaded and the other end lightly loaded, the former end will tend 65 to lag behind the latter when the platform is being lifted and consequently a good landing could not be made nor could the load be well carried.

In Fig. 1 I have shown three differential 70 gear mechanisms 24, 25 and 26' connected in line and to each other by the shafts 26, 27, 28 and 29, suitable standards 30 (Fig. 6) being provided with bearings for these shafts. At the ends of the shaft 26 are 75 rigidly secured the bevel gears 31 and 32 and at the ends of the shaft 27 are secured the bevel gears 33 and 34. To the inner ends of the shafts 28 and 29 are fastened the bevel gears 35 and 36, respectively, to face the 80 gears 31 and 34. The gears 32 and 33 face each other in a similar manner. Between each set of gears, however, there is sufficient space for a planetary bevel gear to be placed with its axis at right angles to the shafts 85 mentioned and mounted on bearings in line with said shafts. In Fig. 3^a is shown a bearing 183 for the arm 37 which carries the gear 39. The bearings for the gears 32 and 33 are indicated at 182 and 182', respectively. The 90 bearings for the arm 37 and the gears 32, 33, are in alinement with each other. These planetary gears are indicated by the reference number 38, 39 and 40 and are always 95 in mesh with the gears 35, 31 and 32, 33 and 34, 36, respectively, at the ends of the shafts. To the lower ends of the arms 37 to the upper ends of which the planetary gears are 100 secured, are connected the valve stems 41, 42 and 43 of the valves 19, 20 and 18, respectively.

The shafts 26, 27, 28 and 29 each have fixed to them a pulley 44, 45, 46 and 47 with which are associated the belts 48, 49, 5 and 4, respectively. The belt 4 is fastened to one 110

corner of the platform 1 at 56 and passes downwardly under the pulley 6 and then to the right horizontally (Fig. 2) under the pulley 47 on the shaft 29 and continues over the pulley 9 to a weight 55. The belt 5 is fastened at 57 near the opposite corner and passes vertically downward under the pulley 7 and over the pulley 46 on the shaft 27 to the weight 54. At the other end of the platform the belts 48 and 49 are attached respectively at the points 58 and 59 and pass under the pulleys 50 and 51, over and under the pulleys 44 and 45 on the shafts 28 and 26 to the weights 52 and 53. The belt 49 passes over also the pulley 60. I desire it to be understood that instead of belts and grooved pulleys I may use sprocket chains and sprocket wheels, which arrangement would be preferable in some cases. In either case it is apparent that there is a tensional reciprocating connection between the bottom of the platform and the differential mechanisms.

If the fluid is admitted to the three valves and the four cylinders simultaneously by opening the supply pipe 21, the platform will be lifted. It will be noticed that the belting is so arranged that the four shafts will rotate alternately in opposite directions. For instance, if the platform be traveling downwardly the shaft 29 will rotate anti-clockwise (Fig. 2); shaft 27, clockwise; shaft 26, anti-clockwise; and shaft 28 clockwise. It will be readily understood that if these shafts rotate with uniform velocities the bevel gears secured to them will simply rotate the planetary gears 38, 39 and 40 about their centers and not tend to bodily move the same so as to operate the valves to which they are connected. But if one of the shafts revolves at a different rate of speed than the one next to it the planetary gears will be moved in one direction or the other to move the valve stem.

Before describing further the operation of the equalizing mechanism, I will explain the construction of the valves 19, 20 and 18, one of which is shown in section in Fig. 3, say the central one of Fig. 1.

62 designates the valve chest through which longitudinally is adapted to move the valve 65, suitable stuffing boxes in the valve chest being provided for lubrication and to prevent leakage. The valve chest is provided with five annular ports 78, 79, 80, 82 and 83. The central chamber 63 communicates with the pipe 64 which leads to the supply pipe 21 and also through the valve ports 81 with the interior of the hollow valve 65.

Near the ends of the valve chest 62 are check valve boxes 68 and 69 to which are connected at 23' and 22', respectively, the pipes 23 and 22 which lead to the end valves 19 and 18. Check valves 70 and 71 are

placed in the separate chambers 73 and 74, respectively, and the check valves 66 and 67 in the separate chambers 85 and 86. Below these chambers are additional separate chambers, such as 89 and 90, Fig. 4.

The hollow valve 65, in addition to the large openings 81 is provided with the series of small openings 76, 77, 93 and 94 so that they shall be helically or elliptically arranged with the axis of the cylindrical valve 65 passing through their centers. These ellipses of small holes are shown slanting toward the right and in each instance one half covered up. That is, half of the number of holes 76 communicate with the annular port 78 when the valve 65 is in central position, while the other half are closed. In a similar manner half of the holes 77 are in communication with the annular port 79, half of the holes 93 with the port 82, and half of the holes 94 with the port 83.

The chamber 87 of the check valve box 68 communicates with the chamber 73 through the opening 72 but fluid cannot enter the annular port 78 through the chamber below 90 from chamber 73 by reason of the check valve 70. Chamber 87 also communicates with the chamber below the chamber 74 through the opening 92 and fluid can be forced thence into the chamber 74 past the 95 check valve 71. The chamber 74 communicates with the port 63 through the port 75, half of the port holes 77, the interior of the cylindrical valve 65, and the valve ports 81.

The operation of the construction thus far described is as follows: Assuming a change valve in the supply pipe to be moved to pressure-supplying position and the valves 19, 20 and 18 in their central positions, the fluid will flow through the central valve from annular chamber 63 through the holes 81, to and through half of the holes 76 at one end and half of the holes 94 at the other end of the valve 65. The fluid passes also through half the holes 77 on one hand and half the 110 holes 93 on the other hand. The fluid through the holes 77 and 93, however, cannot be forced out of the check valve boxes by reason of the check valves 71 and 66. The fluid passing through the holes 76 into the 115 annular chamber 78 will lift the check valve 70 against the force of gravity and flow into chamber 73, through opening 72 into chamber 87 and thence through the port 23' into the pipe 23 and through the same to the 120 valve 19. In this valve the fluid enters the central annular chamber 63 and passes through the check valve box 68', pipe 16 to the cylinder 13. The fluid also passes from the annular chamber 63 through the openings 81, half of the holes 94, chamber 83, port hole 84 into chamber 90, past the check valve 67 into the chamber 86, port 91, chamber 88, port 22', pipe 22 to valve 18. Through this valve the fluid passes in a similar manner 125 130

through the check valve box 69", pipe 15 to cylinder 11. Of course the fluid passes also through the check valve box 69' of the valve 19 to the pipe 17 and cylinder 12, and 5 through the check valve box 68", to the pipe 14 and cylinder 10. Each valve being in central position the rate of flow of the fluid will be the same to each cylinder and the platform will be lifted at substantially uniform velocities at all points. This will cause 10 the various shafts to be rotated at equal rates of speed and consequently the planetary gears will simply rotate about their centers as before explained. Suppose, however, 15 that a heavy load is placed over the plungers 3 and 3' at one end of the platform and there be a light or practically no load at the other end. The end bearing the heavy load will tend to lag behind the other end. 20 Therefore, more fluid must be supplied to the valve 19 than to the valve 18 and this is done automatically with my arrangement. The lighter end will travel faster than the heavier end and in so doing will rotate the 25 shaft 27 in an anti-clockwise direction faster than the shaft 26 is rotated in a clockwise direction. This will effect a movement of the planetary gear 39 bodily to the left and of the valve stem 42 to the right. A larger 30 number of ports 76 will then be opened into the annular port 78 while a corresponding number of the ports 94 will be closed from communication with the port 83. It is, therefore, seen that fluid will flow at a 35 greater rate of speed to the valve 19 and at a less rate of speed to the valve 18 at this time than when the valve 65 is in central position. In a similar manner if one corner is more heavily loaded than the one next to it, 40 as for instance, if there is a heavier load on the plunger 3' than on the plunger 3, the cylinder 13 will receive more fluid than the cylinder 12 until the platform becomes level. With any unequal load the equalizing action 45 is constantly and gradually taking place in the manner stated so long as the platform is being lifted.

In the opposite direction of the platform, that is when the same is descending, the 50 most heavily loaded part of the platform will tend to descend the faster. The plunger adjacent that point must therefore be retarded and this is done automatically by means of the same valves as before but using 55 other portions of the check valve boxes and other elliptically arranged ports in the valve cylinder 65. Of course, in descending the fluid must be exhausted from the cylinders and in order to allow the lighter portions of 60 the platform to descend at the same rate of speed as the heavier portions the cylinders under the lighter portions must be exhausted faster and those under the heavier portions retarded in exhausting. Suppose, then, 65 that the plungers 2 and 2' are the more

heavily loaded and the platform at that end starts to descend more quickly than at the other end. The shaft 27 will be rotated by means of the weight 54, belt 5 and pulley 46 in clockwise direction at a greater rate of 70 speed than the shaft 26 will be rotated in the opposite direction. The planetary gear 39 will therefore be moved bodily to the right and the valve 65 to the left. The exhaust fluid is constantly flowing at this time 75 from cylinders 12 and 13 through valve 19 to chamber 87, through port 92, past check valve 71, through chamber 74, port 75, half of the holes 77, port holes 81, to the exhaust port of the change valve in the main supply 80 pipe 21. The fluid is also exhausting to the supply pipe exhaust port from the cylinders 10 and 11, through valve 18, pipe 22, chamber 88, port 95, chamber 89, past check valve 66, chamber 85, port 96 and annular chamber 82, through half the holes 93, to the ports 81 and thence to the supply pipe 21. But when the valve 65 is moved to the left 85 the holes 93 are throttled while those at 77 will be opened wider. The exhausting of the fluid from the cylinders 10 and 11 is therefore retarded and that from the cylinders 12 and 13 increased. This equalizing action takes place constantly as before and maintains the platform substantially level. 90 As in the case of the platform ascending, so also when the same descends the valves 19 and 18 may also be operated to allow the fluid to escape from one cylinder, as 10, faster than the next adjacent one, as 11. 100

Figs. 5, 6 and 7 show a modified form of valve, three of which are connected to the platform lifting means (Fig. 5) in exactly the same manner as is done in Figs. 1 and 2. But I provide manual means for operating 105 the valves instead of automatic means and therefore the check valve mechanism is unnecessary.

Fig. 6 shows the details of the valve mechanism in section. I provide a revoluble cylindrical sleeve 97 to fit closely with the cylindrical piston valve 65. This sleeve has secured to its right-hand end the shaft 101 which passes through the right-hand end of the valve 65 and is movable longitudinally 110 in a bearing in the standard 100. The shaft 101 is provided with a squared portion 102 on which is fitted a crank arm 103 which has secured at its outer end a laterally projecting pin 104. From Fig. 5 it will be seen 115 that a rod 105 is connected to the pin 104 of the crank arm of each of the valve mechanisms so that when said rod is moved longitudinally the internal sleeve 97 of each valve will be rotated about its longitudinal axis. 120 It will be noticed further, that each of the valves may be moved longitudinally without interference with the operation of the crank arms for in such case the squared ends 125 of the shafts will simply slide through the 130

square holes in the hubs of said arms. The pins 104 may slide in the bar 105.

The inner sleeve 97 is provided with series of circularly arranged holes which are 5 adapted to register with corresponding holes in the cylindrical portion of the valve 65. The valve chest 120 is provided with ports 117, 118 and 119 which are shown in Fig. 6 as screw-threaded to receive the pipes 22, 64 10 and 23, respectively, assuming the valve to be the central one of Fig. 5. The screw-threaded ports communicate with annular chambers or ports 121, 122 and 123 which surround the valve cylinder 65 at the open- 15 ings therein.

The operation is as follows: Assuming each valve to be in the position shown in Fig. 6 the supply fluid will pass through the ports 118 and 122, the holes 114 and 115 in 20 the valve 65, and holes 108 and 109, respectively, registering therewith, into the interior of the cylindrical sleeve 97. The fluid may then pass through the openings 107 and 110 in the inner cylinder, openings 113 25 and 116, respectively, in the outer cylinder, into the chambers 121 and 123 and through the ports 117 and 119, pipes 22 and 23, valves 18 and 19, pipes 14 and 15 to the cylinders 10 and 11 and pipes 17 and 16, to 30 the cylinders 13 and 12. The fluid cannot pass through the openings 106 or 111 as they are closed at this time, that is, they do not register with the openings 112 or 117' in the outer cylinder. Now by moving the 35 rod 105 longitudinally the openings shown in Fig. 6 may be throttled to any extent desired and therefore the speed with which the platform is being lifted may be controlled or it may be stopped by rotating the 40 inner sleeve to entirely close the circular series of holes. It will be seen that when the valve is in central position the holes 113 and 116 are half throttled by the valve seat. Should, therefore, one end of the platform 45 be lifted more rapidly than the other due to a lighter load, the planetary gear would be moved bodily and consequently the valve would be moved longitudinally. This operation would effect a wider opening of one 50 set of ports and a throttling of the other set. Suppose the plungers 2 and 2' are being lifted faster than the plungers 3 and 3'. This will effect an automatic movement of the valve 65 to the right. The openings 116 55 and 110 will be opened wider while those designated by the reference numbers 113 and 107 will be throttled. The fluid can therefore flow to the valve 19 at a greater rate of speed than to the valve 18. This will tend 60 to equalize the rate of speed at which the plungers are being lifted and therefore maintain the platform substantially level. When the platform descends the reverse movements of the plungers tend to take 65 place, that is, the heavier end will tend to

descend faster than the lighter end. Assuming the platform to be loaded as before the valve would again be moved to the right and the fluid would be exhausted more quickly from the cylinders 12 and 13 than 70 from the cylinders 10 and 11. But the reverse of this condition is required. Therefore, when the platform is allowed to descend the rod 105 must first be moved to such a position as to rotate the inner sleeve 75 97 and close the openings 113 and 116 and open the holes 112 and 117'. That is, the holes 106 must register with the holes 112 and the holes 111 with the holes 117'. In central position each of the series of holes 112 80 and 117' are half throttled by the valve seat. In the new position of the valve sleeve, when the valve is moved to the right the exhaust from the valve 18 will be more rapid than from the valve 19. The lighter end of the 85 platform will then tend to descend more rapidly and catch up with the loaded end, where the exhaust from the cylinders will be retarded. The final result will be to keep the platform substantially level. 90

In Figs. 8, 9 and 10 I have shown an application of the equalizing gears to valves of ordinary construction. This type of valve is shown in Fig. 10 in section and is what is known in elevator practice as a 95 three-way-change valve.

In Fig. 8 I have shown four valves, one for each plunger. Upon the shaft 135 which extends throughout the length of the mechanism are fixed bevel gears 136, 137, 138 and 139. Loosely mounted on said shaft are the bevel gears 140, 141, 142 and 143 on the hubs of which are secured the 100 pulleys 179, 174, 180 and 165.

Fixed to the four corners of the platform 1 are the belts 171, 173, 161 and 162 which pass vertically downward to idle pulleys 170, 172, 164 and 163 and then horizontally to the pulleys 179, 174, 180 and 165, respectively. The belts pass under all the last 110 named pulleys to additional idle or direction pulleys 178, 175, 181 and 166 and thence to weights 177, 176, 182 and 167, respectively.

The shaft 135 may be manually rotated either by the gearing 129 and handle 128 or by means of the handle 130 and shaft 131 arranged at a point above the platform but within reach of the operator. This shaft 131 has fixed to it a pulley 132 which is connected by a belt 133 to another pulley 134 fixed to the shaft 135. Upon movement of the shaft 135 in a clockwise direction the link 43 will be moved toward the left as viewed in Fig. 8 and toward the right as 115 viewed in Fig. 10. To the link 43 is connected the valve stem 160 to which are secured the balancing piston 158 and the valves 154 and 155 which are adapted to move longitudinally in the valve chest 152. 120 130

As shown in Fig. 10 the valves are in central or closed position so that the fluid entering the space between the valves from the cylinders through the supply port 153 can go no farther, nor can fluid from the supply port 157 enter the cylinders. If, however, the valve stem 160 is moved to the right the fluid can pass from the supply port 157 through the openings 156 in the lining and thence to and through the port 153 and to the cylinder connected therewith. Therefore when the shaft is turned in a clockwise direction all the change valves will be opened and the platform will ascend. As it does so, however, the valves will be again closed by the automatic movement of the planetary gears in the opposite direction. The latter movements of the planetary gears will vary with the load on the different parts of the platform, those parts moving the faster throttling the fluid to the nearest cylinders more than the slower moving portions. It will be seen, however, that the motion of the shaft 135 must be kept up, otherwise the change valves will be closed as soon as the platform has moved sufficiently to effect the movements of the planetaries back to their original positions. If the motion of the shaft 135 is continued manually the motion of the platform will also continue only stopping when the plungers have reached predetermined limits. While the platform is moving there is always a tendency for the loose gears to catch up with the fixed gears and at rates depending upon the distribution of load on the platform, the effect being to maintain the platform substantially level irrespective of such distribution of load. Of course, when the platform is allowed to descend the fluid is exhausted from the cylinder through the exhaust ports 159 of the change valves, to the exhaust pipe 169. The operation of the equalizing apparatus would be the same in this case only in reverse direction.

While the arrangement shown in Figs. 8, 9 and 10 is not entirely automatic it employs ordinary valves and admits of very prompt governing.

As shown in Fig. 9, the plungers or rams may, if desired, be hinged to the platform, as by ball and socket joints, but ordinarily the flexibility of the platform will be sufficient to take care of any tendency of an uneven load to bend the rams, this tendency being reduced to a minimum by the use of my invention.

Having thus described my invention and without limiting myself to the precise construction of details or arrangement of parts, what I claim and desire to secure by Letters Patent of the United States is:

1. The combination with a platform, of means for lifting the same, means for con-

trolling said lifting-means, differential 65 planetary mechanism for actuating said controlling-means, and means operatively connected to the platform for throwing said differential mechanism to various positions.

2. The combination with a platform, of 70 means for lifting the same, means for controlling said lifting-means, differential planetary mechanism for actuating said controlling-means, and a reciprocating tensional connection operatively connected with said 75 platform and said differential mechanism for actuating the latter.

3. The combination with a platform, of a 80 plurality of lifting motors and controlling means therefor, differential planetary mechanisms for actuating said controlling-means, and a plurality of tensional connections each operatively connected with said platform and adapted to independently actuate each differential mechanism.

4. The combination with a platform, of 85 multiple moving-means therefor, controlling means for said moving-means, co-acting differential planetary mechanisms for operating said controlling-means, and a plurality of tensional connections between the platform and differential mechanisms to actuate the latter to various degrees and effect an even lifting of the platform irrespective of an uneven distribution of load on 90 said platform.

5. The combination with a platform, of a 95 hydraulic motor for lifting the same, a valve for controlling said motor, differential planetary mechanism for operating said valve, and a tensional connection between said platform and said differential mechanism to actuate the latter and throw said valve to various degrees of opening.

6. The combination with a platform, of 100 a hydraulic motor for lifting the same, a valve for controlling the motor, differential planetary mechanism for operating said valve, and a reciprocating tensional connection operatively connected with said platform and differential mechanism for actuating the latter.

7. The combination with a platform, of 105 a plurality of lifting hydraulic motors and valves therefor, a plurality of co-acting differential planetary mechanisms for operating said valves, and a plurality of tensional connections each operatively connected with said platform and differential mechanisms for operating the latter.

8. The combination with a platform, of 110 three or more hydraulic plungers connected therewith, hydraulic cylinders for said plungers, valves for controlling the passage of fluid to and from said cylinders, differential gearing arranged in alinement for actuating said valves to various degrees of opening to vary the rate of flow of fluid to

the various cylinders, and means connecting said platform and differential gearing for automatically operating the latter.

9. The combination with a platform, of a plurality of motors for lifting the same, a plurality of valves for controlling said motors, planetary gearing for actuating said valves, and means connected to the platform for operating said gearing.

10. The combination with a platform, of a plurality of hydraulic motors for moving the same, a plurality of valves for controlling said motors, a plurality of differential planetary mechanisms corresponding in number to the number of valves for actuating said valves to various degrees of opening, and means connected with the platform for automatically operating said differential mechanisms.

11. The combination with a platform, of three or more hydraulic motors, a plurality of valves for controlling said motors, differential gearing coöperatively connected in alinement with each other for actuating said valves to various degrees of opening, and means for operating said differential gearing.

12. The combination with a platform, of hydraulic motors therefor, valve mechanism for controlling said motors, and planetary gearing operating said valve mechanism, the latter being constructed and arranged when operated by said gearing to simultaneously increase the rate of flow of fluid to the motors most heavily loaded and decrease the rate of flow to the motors less heavily loaded.

13. The combination with a platform, of hydraulic motors therefor, valve mechanism for controlling said motors, and planetary gearing operating said valve mechanism, the latter being constructed and arranged when operated by said gearing to simultaneously increase the rate of flow of fluid to the motors heavily loaded and decrease the rate of flow to the motors lightly loaded when the platform is being lifted and to control the exhaust reversely when the platform is descending.

14. The combination with a platform, of distributed hydraulic motors therefor, valves for controlling said motors, differential gearing comprising a plurality of planetary gears, connections between said planetary gears and said valves, and means for actuating said differential gearing to effect an even lifting of the platform irrespective of the load thereon.

15. The combination with a platform, of hydraulic motors for lifting the same, a plurality of valves for controlling said motors, differential gear mechanisms comprising planetary gears and corresponding in number to the number of said valves and arranged in substantial alinement with each other, valve-actuating connections between

the planetary gear of each of said gear mechanisms and each of said valves, and connections corresponding in number with the number of hydraulic motors for operating said differential gear mechanisms.

16. The combination with a platform, of a plurality of distributed hydraulic motors for lifting said platform, valves for controlling said motors, planetary bevel gear mechanism with connections for operating said valves, and means for automatically operating said planetary bevel gear mechanism and said valves to maintain the platform substantially level at all times.

17. The combination with a platform, of hydraulic motors therefor, valves for controlling said motors, a plurality of shafts in alinement with each other, bevel gears secured to both ends of the intermediate shafts and to the inner ends of the outside shafts, planetary bevel gears mounted between each pair of facing bevel gears on said shafts, valve-actuating means connected to said planetary gears, a plurality of wheels one fastened to each of said shafts, a plurality of connections one for each of said wheels and each secured to the platform, means for directing said connections, and means for keeping said connections taut.

18. The combination with a platform, of hydraulic means for moving the same, valve mechanism for controlling said moving means comprising a main valve, check valves, and sets of ports in the main valve for operatively connecting the same with the check valves, and means for automatically operating said valve mechanism to simultaneously open one set of ports therein and close another set and place both sets of ports in co-operative relation with half of the number of said check valves.

19. The combination with a platform, of hydraulic means for moving the same, a main valve provided with a plurality of series of supply ports, a corresponding number of supply check valves to coöperate with said supply ports, said main valve having also a plurality of series of exhaust ports, a plurality of exhaust check valves to coöperate with said exhaust ports, and means for moving said main valve to supply or exhaust position.

20. The combination with a platform, of hydraulic means for moving said platform, a main valve provided with two series of graduated supply ports and also two series of graduated exhaust ports, check valves to coöperate with said supply and exhaust ports, and means for simultaneously opening one series of supply ports and throttling the other series when the platform is being lifted and for simultaneously opening one series of exhaust ports and throttling the other when the platform is descending.

21. The combination with a platform, of

a plurality of motors for lifting the same, a plurality of valves for controlling said motors, check valves associated with the aforesaid valves, planetary gearing for actuating said first-named valves, and means connected to the platform for operating said gearing.

22. In valve mechanism, the combination with a hollow valve having two sets of ports at each end, of a valve casing having chambers coöperating with said ports, and check valves in said chambers, the ports and valves being constructed and arranged to cause the supply to pass into the interior of said hollow valve, out of the same through certain sets of ports, and past certain check valves, and the exhaust to pass the other check valves into the interior of the hollow valve, and thence out of same.

23. The combination with a platform, of

a plurality of hydraulic motors for lifting the same, a plurality of valves each having four series of ports, planetary differential gear mechanisms corresponding in number to said valves, tensional connections between the platform adjacent the respective motors and said differential gear mechanisms, said tensional connections corresponding in number to the number of said motors, and check valves interposed between said valves and said motors, the number of said check valves corresponding in number to the number of series of ports in said first-named valve.

In testimony whereof, I have signed my name to this specification in the presence of two subscribing witnesses.

ANDREW M. COYLE.
